UNITED STATES PATENT OFFICE.

HENRY GEISENHÖNER, OF SCHENECTADY, NEW YORK, ASSIGNOR TO THE GENERAL ELECTRIC COMPANY, OF NEW YORK.

INDUCTOR DYNAMO-ELECTRIC MACHINE.

SPECIFICATION forming part of Letters Patent No. 640,760, dated January 9, 1900.

Application filed November 14, 1898. Serial No. 696,333. (No model.)

To all whom it may concern:

Be it known that I, HENRY GEISENHÖNER, a citizen of the United States, residing at Schenectady, in the county of Schenectady, State 5 of New York, have invented certain new and useful Improvements in Inductor-Dynamos, (Case No. 482,) of which the following is a specification.

My present invention relates to the construction of inductor-dynamos, and more particularly to the revolving inductor of such machines. In practice these machines are sometimes driven at very high speeds, and it has been found that they set up a very disagreeable "howl" or vibration. Many attempts have been made to remedy this difficulty, some of which have lessened it, but none of which have been entirely successful. It has been due to a great extent to the shape of the 10 inductor, which sets up harmonic vibrations in its revolutions. It is the object of the present invention to prevent this by building out the inductor to a substantially cylindrical form with materials to some extent at least 15 non-resonant in character. It is manifest that most materials except metals are unsafe on account of the centrifugal stress to which these structures are subjected. I prefer, therefore, to build the iron part of the inductor 20 of the usual laminated construction and attach it to a solid metallic body, filling the cut-away part of the iron structure with laminations of brass and some non-resonant insulating material, such as compressed fiber. 25 By this arrangement I am enabled to check to a great extent harmonic vibration, so that the noise from the alternator is minimized and in machines of ordinary sizes eliminated. At the same time by dovetailing the parts together I get a structure which is capable of 30 enduring the strain of the highest speeds used in these machines.

The accompanying drawings show my invention.

Figure 1 is a section of an inductor-alternator with a part of the revolving inductor shown in side elevation, and Fig. 2 a section through the revolving inductor.

In Fig. 1, A is the shaft of the machine, of 45 which B is the armature-frame. M is one of

the armature-coils, C the field-magnet winding, and D is the armature-iron. These parts are old and of any well-known construction.

The revolving inductor consists of a solid approximately cylindrical body of metal G, 55 to which the inductor-poles E are secured by dovetails and the usual end plates F F' and rings H threaded upon the body G. At I I' are shown the non-magnetic laminations, which are preferably of brass or gun-metal 60 and are separated by insulation, such as hard fiber K.

The configuration of the different parts will be better understood from Fig. 2, in which E' is one of the laminations of the inductor-iron, provided with dovetails e e, which mesh with a similar construction on the inductor-body G. The brass or gun-metal plates I' are also provided with dovetails i, which fit into proper grooves on the inductor-body and 70 into the pole-pieces. To lessen the weight and the consequent centrifugal strain, openings i' i' are made in the brass and fiber plates. These openings also serve to still further eliminate eddy-currents and to cool the in- 75 ductor.

What I claim as new, and desire to secure by Letters Patent of the United States, is—

1. The combination with an inductor having radial pole-pieces, of a light, hollow, non-magnetic cooling structure secured to the inductor, and filling the spaces between the pole-pieces to present with the latter a substantially cylindrical surface. 80

2. A rotatable inductor with radially-extending pole-pieces and provided with alternate layers of non-magnetic metal and non-resonant insulation, which fill the spaces between the pole-pieces. 85

3. In an inductor, the combination of a supporting-core, laminated poles secured to the core, and intervening plates of alternate insulating material and non-magnetic metal secured to the core and filling out the space between the poles so that the envelop of the in- 90 ductor is substantially a cylinder. 95

4. The combination in an inductor, of the supporting-core, the laminated iron forming the pole-pieces dovetailed to the core, and the plates of non-magnetic metal, such as brass, 100

and of insulation, dovetailed to the core and the pole-pieces; the whole forming substantially a cylinder.

5. The combination with an inductor having radial pole-pieces, of non-magnetic material interlocked with the inductor structure and filling the spaces between the pole-pieces.

6. A rotatable inductor comprising a separate core, radial pole-pieces, and non-magnetic material interlocked with said core and pole-pieces and filling the spaces between the poles.

7. A rotatable inductor comprising a separate core, pole-pieces secured thereto, and non-magnetic material secured to the core and filling the spaces between the pole-pieces.

8. A rotatable inductor comprising a separate core, pole-pieces secured thereto, and non-

magnetic material secured to the pole-pieces and filling the spaces between said pole-pieces.

9. A rotatable inductor comprising a separate core, pole-pieces secured thereto, and non-magnetic material secured to the core and pole-pieces, and filling the spaces between the pole-pieces.

10. A rotatable inductor with radially-extending pole-pieces and provided with non-magnetic laminæ filling the spaces between the poles, each of which laminæ is interlocked with the inductor structure.

In witness whereof I have hereunto set my hand this 12th day of November, 1898.

HENRY GEISENHÖNER.
